UNITED STATES PATENT OFFICE.

MARGARET L. SHEPARD, OF WATERTOWN, NEW YORK.

DESIGN FOR A SKIRT-SUPPORTING BELT.

SPECIFICATION forming part of Design No. 33,119, dated August 28, 1900.

Application filed June 28, 1900. Serial No. 21,941. Term of patent 7 years.

To all whom it may concern:

Be it known that I, MARGARET L. SHEPARD, a citizen of the United States, residing at Watertown, in the county of Jefferson and State 5 of New York, have invented and produced a certain new and useful Design for a Skirt-Supporting Belt; and I do declare the following to be a full, clear, and exact description of the invention, such as will enable others skilled 10 in the art to which it appertains to make and use the same, reference being had to the accompanying drawings, and to the letters of reference marked thereon, which form a part of this specification.

15 This invention relates to a novel design for a skirt-supporting belt, and the general design of the belt is clearly illustrated in the accompanying drawings, in which—

Figure 1 is a perspective view of the belt. 20 Fig. 2 is a cross-sectional view through the belt and longitudinally of one of the hooks.

Reference now being had to the details of the drawings by letter, the belt has semicircular outlined apertures near each end of the 25 widened portions A and C, as seen at B B. The narrow portions of the belt between said wide portions terminate at the ends of the

curved marginal outlines of said apertures B B. On the outer surface of the widened portions of the belt at regular intervals are 30 scalloped or concaved portions E along the longitudinal marginal edges thereof, and the inner ends of said concaved portions terminate at the ends of the convex portions G. Projecting from the ends of said convex portions are round pins H, the upper ends of which are curved over the upper edges of the belt and have their downwardly-disposed ends pointed. On the inner faces of the widened parts of the belt at regular intervals 35 from one another and opposite the convexed and concaved portions on the outer faces are ribbed portions K.

Having thus described my invention, what I claim is— 45

The design for a skirt-supporting belt, substantially as shown and described.

In testimony whereof I affix my signature in presence of two witnesses.

MARGARET L. SHEPARD.
